FISH LURE

Fred Hammon, V.A. Center, Bonham, Tex. 75418

Filed June 28, 1967, Ser. No. 7,630

Term of patent 14 years

(Cl. D22—27)

FIG. 1

FIG. 2

FIG. 1 is a front view of a fish lure embodying my new design; the undisclosed opposite side is a mirror image of the side shown; and

FIG. 2 is a side elevation partially shown for ease of illustration.

I claim:

The ornamental design for a fish lure, as shown and described.
